1,698,707

UNITED STATES PATENT OFFICE.

SAMUEL JACOB AARON, OF BROOKLYN, NEW YORK.

FIXTURE SUPPORTING AND CONNECTING DEVICE.

Application filed July 23, 1926. Serial No. 124,526.

My invention relates to certain new and useful improvements for electrically connecting electric fixtures to a source of power and for mechanically supporting such fixtures.

5 One of the objects of the invention is to provide devices whereby the installation of any electrical fixture may be accomplished by one simple operation, the operation serving to establish electrical connection to the fixture and the source of power and also serving to provide mechanical support for the fixture,—bracket, or fan.

Another object of the invention is to eliminate the use of hickies, or any solder, paste, 15 rubber or friction type in the installation of electric lighting fixtures, brackets, fans or other electric fixture.

Another object of the invention is to provide a combined outlet box and fixture supporting device of simple and compact construction. A further object of the invention is to provide a combined outlet box and fixture supporting device, the parts of which are so designed and cooperate with each 25 other in such a manner that, in addition to serving as a means for electrically connecting the electric fixture, or the like it may also serve to mechanically support the fixture.

In the drawings, Figure 1 is a plan view of 30 one embodiment of my invention.

Figure 2 is a sectional view on the line 2—2 of Figure 1.

Figure 3 is a sectional view on the line 3—3 of Figure 1.

35 Figure 4 is a plan view of the device having the supporting and connecting block and cover removed therefrom.

Figure 5 is a detail section on line 5—5 of Figure 3.

40 Figure 6 shows the insulating element of the plug.

Figure 7 is a diagrammatic showing of a lighting system and the manner in which the combined outlet box and supporting device 45 cooperate therewith.

Figure 8 is a perspective of the supporting and connection element.

Referring to the drawings reference numeral 10 indicates one end of a lighting fixture which usually consists of an exteriorly threaded pipe. The plug 11 which is readily and permanently mounted on the threads of the electric fixture 10 consists of an integral block of metal which may be brass or copper 50 or the like. The block has a longitudinal passage 12 which is provided with internal

threads at one end thereof, which serve to receive the threaded portion of the fixture 10. The passage 12 serves to receive the electric lead wires 13—14 and is so proportioned with 60 relation to the outer diameter of the main body 15 of the block that the walls remain of substantial thickness and are, therefore, capable of supporting a weight many times the weight of electric lighting fixtures or other 65 electric devices. In the form of the invention shown in the drawings, the main body portion 15 of the plug has an outer diameter exceeding one inch while the diameter of the passage 12 is approximately less than one-half of an inch. The main body portion 15 is provided with external threads 16 which are of the same pitch as the threads commonly 70 used on electric bulbs which are provided with corrugated metallic shells. The wall of the passage 12 is provided with a sloping portion 17 at its forward end, this portion being provided with an internally threaded recess 18 adapted to receive the binding post 19 for connecting the wire 13 to the plug 11. 75

The forward end of the main body portion has an oblong recess so shaped that the head 21 of the insulating body 20 shown in Figure 6 will fit snugly into said recess, while the shank 22 of said insulating body will enter 80 the passage 12 as shown in Figures 2 and 3. The shank 22 is provided with a groove 23 on one face thereof to permit of the passage of wire 13 for connection to the binding post 19. The other face of the shank 22 is provided 85 with a deeper groove 24, the groove being extended by the passage 25 in the head 21. The forward face of the head 21 is provided with a recess which receives the metallic plate 26, the plate being held in place by the metal eyelet 27 which fits snugly against the walls 90 of the passage 25. The plate 26 is also provided with a threaded passage 26' which receives the binding post 28 for the electrical connection of the wire 14 thereto. The head 100 of the binding post constitutes the center contact of the plug.

The plug body is directly connected to the electric fixture and the grounded wire 13 is connected to the plug, whereby the plug and 105 the electric fixture are properly grounded.

It will be seen from the above that the plug consists of an externally threaded metallic body made of a solid metal block and a small body of insulating material which is so 110 shaped that it may be readily assembled and disassembled from the plug. The body of

insulating material 20 is not anchored to the plug but is so designed that it may be easily removed and replaced for the purpose of providing ready access to the binding post 19, and 5 so shaped as to prevent it from turning with relation to the plug body. When the wires 13 and 14 are properly connected as shown they serve to prevent the loss of the insulating body 20.

10 The combined outlet box, and supporting and connecting devices comprises a casing 30, a cover 31, a supporting block 32 and two bodies of insulating material 33 and 34.

The casing 30 is provided with apertures 15 35 in the bottom thereof. These apertures are designed to receive screws whereby the casing may be mounted on the ceiling or on the wall of the room or it may be mounted on a joist or a beam or any other structure element of the walls or ceiling. The casing is 20 so constructed as to provide integral upstanding hollow studs 36. The passage in these studs are designed to receive armored cables which may be clamped in position and 25 electrically grounded by the screws 37. The space between the adjacent studs 36 and the upright wall of the casing is somewhat thickened and is provided with an interiorly threaded passage 38 to receive the screws 39' 30 which hold the cap 31 against the casing 30. A body of insulating material 33 is so shaped as to fit snugly within the casing and has 35 mounted thereon the terminal bars 39 and 40 which are held in place by means of screws 41, the lower portion of the openings for such screws being filled with sealing wax. The terminal bar 39 is provided with binding post washerhead screws 42, 43 and 44 while the terminal bar 40 is provided with binding 40 post washerhead screws 45, 46, 47 and 48. The outer face of the insulating body 33 also has mounted thereon a metal strip 50 which is held in place by screw 51 in the same manner that the terminal bars 39 and 40 are held 45 in place. One end of the strip 50 is provided with a threaded passage 52 and extends over the center of the body 33 while the other end is provided with a binding post 53. The plug receiving resilient jack 54 is mounted 50 in a recess of the body 33 and is mechanically and electrically connected to the terminal 39 by means of one of the screws 41.

The insulating body 34 is cross shaped and is disposed on the body 33 in such a manner 55 as to divide the surface thereof into four quadrants as shown in Fig. 4. This arrangement provides the space necessary for leading the wires from the armored cables to their respective binding posts. When these insulated wires are properly connected they lie 60 below the top of the casing and the box presents a compact and neat appearance. The insulating body 34 is provided with a counter-sunk passage 55 through the center thereof 65 and a screw 56 having a flanged washer 57

mounted thereon passes through the passage 55 and engages the threaded passage 52 in the strip 50 for holding the body 34 in place. The screw and washer together constitute the center contact of the supporting device. The 70 body 34 has a concentric upstanding stud 66.

The supporting and connection block 32 consists of a heavy metallic body provided with an interiorly threaded central recess 58 which provides the annular shoulder 59. The 75 outer face of the block is curved to provide the flanged portion 60. The block is provided with two diametrically opposed recesses 61 which cooperate with corresponding projections 62 on the cap to hold the socket 80 against any possible rotation. A sleeve made of flexible insulating material 63 is interposed between the cap 31 and the block 32. A pair of screws 39' serve to hold the cap in place 85 with relation to the casing and at the same time hold all of the parts of the combined outlet box and supporting and connecting device in assembled relation.

The block 32 carries a jack plug 64 integral therewith which is adapted to engage 90 the jack contacts 54 and be gripped thereby, forming the ground contact. The block is thereby electrically connected to the distributing plate 39 and is readily detachable therefrom. The block rests upon the face 65 of the insulating body 34 and receives the upstanding stud 66 in its opening 67 which is somewhat smaller than the passage 58.

In the construction shown four passages 100 receive four armored cables. It is obvious, however, that the construction may be modified to receive any number of armored cables desired. In the present instance one of the armored cables 71 is connected to the source of power and carries the two main wires 72 105 and 73, 72 being connected with the binding post 42 on the distributing plate 39 and 73 being connected to the binding post 46 on the distributing plate 40.

Another armored cable 74 has one of its 110 wires 75 connected to the binding post 53 and the other of its wires 76 connected to the binding post 47. The wires 75 and 76 of the last mentioned cable are carried to a wall switch shown diagrammatically in Figure 7. The armored cable 77 carries two wires, one of which is connected to the binding post 43 and the other is connected to the binding post 45. The armored cable 78 also carries two wires, one of which is connected to the binding post 44 and the other is connected to the binding post 48. These two cables are designed as branch feed lines and may be conducted to other portions of the room or to other portions of the building if desired. 115

In the construction shown, the combined outlet box, supporting and connecting device constitutes a small compact construction of few parts which is designed to receive a feed cable and a plurality of take-off cables for 120 130

feeding other circuits. The combined outlet box, supporting and connecting device is also so constructed that the take-off cable for a wall switch is readily provided. It should be noted that if desired wire 75 may be connected to one of the binding posts on the distributing plate 39 and the wires 75, 76 may serve for an additional circuit. For this purpose, however, an electrical connection must be established between the binding post 53 and the distributing plate 40 in order to establish proper electrical connection between the center contact 57 and the distributing plate 40.

The plug and the supporting and connecting block are each so designed that they can sustain a weight greatly in excess of the weights of electric fixtures such as lighting fixtures or electric fans or the like, and the threaded engagement between the plug and block is such as to sustain such weights. The weight carried by these elements is transmitted through the cover and the casing directly to the structural element on which the casing 31 is mounted. The fixture 10 being directly and fixedly attached to the plug 15, it is sufficient for the operator to merely screw the plug 15 home into the block 32 and thereby accomplish both the electrical connection and the mechanical installation of the fixture, without any reconnecting or resoldering of wires.

The two insulating bodies 33 and 34 are shown herein as separate bodies. It is obvious, however, that if desired these two bodies may be formed of one piece of material and made integral therewith. This is only illustrative of the numerous modifications to which the construction shown may be subjected and, therefore, I do not wish to be limited to the specific construction shown.

I claim:

1. A combined outlet box and supporting and connecting device comprising a casing having a plurality of openings in its bottom adapted to receive armored cables, a body of insulating material, within the casing, a pair of terminal plates mounted on said body, a plurality of binding posts on each of said terminals, an element of a separable contact device mounted on said body and electrically connected to one of said terminals, an interiorly threaded supporting and connecting block, another element of a separable contact device mounted on said block for cooperation with said first contact element, a cover for holding said parts in assembled relation, an insulating sleeve interposed between said cover and said block, and a plug cooperating with said block, said plug consisting of an exteriorly threaded metallic block having an internally threaded longitudinal passage, and an insulating block lodged in one end of said passage, and a contact on said insulating block.
2. A device affording electrical connection and mechanical support for a heavy electric fixture comprising a substantially solid metallic block having an interiorly threaded recess, an outlet box having a plurality of openings to receive the feed wires and lead

wires, a body of insulating material within said outlet box and between the said block and the bottom of said outlet box, a flange integral with said block and means for mechanically connecting said block and said casing.

3. An electrical connecting and mechanical supporting devices for electric fixtures comprising a supporting member, a substantially solid metallic block having an integral flange and an interiorly threaded recess capable of receiving the conventional threaded lamp base, an insulating body interposed between said supporting member and the flanged end of said block, said flange having a recess therein, and means for mechanically connecting said block, insulating body and said support member into a unitary structure, said means comprising an element engaging said flange and having a projection engaging said recess in the flange.

4. A supporting and connecting device comprising a metallic block having a longitudinal passage, and exterior threads, one end of the passage having internal threads for connection to a fixture, and a body of insulating material lodged in the other end of said passage bearing an electrical contact thereon.

5. A combined outlet box and supporting and connecting device comprising a casing having a plurality of openings in its bottom adapted to receive armored cables, a body of insulating material, a pair of terminal plates mounted on said body, a plurality of binding posts on each of said terminals, a separable

element of a contact device mounted on said body and electrically connected to one of said terminals, an interiorly threaded supporting and connecting block, another element of a separable contact device mounted on said block for cooperation with said first contact element, a cover for holding said parts in assembled relation, an insulating sleeve interposed between said cover and said block, and a plug cooperating with said block, said plug consisting of an exteriorly threaded metallic block having an internally threaded longitudinal passage, and an insulating block lodged in one end of said passage, and a contact on said insulating block.

6. A combined outlet box and connecting device comprising a casing having formed integrally therewith a plurality of hollow studs disposed on the bottom of said casing, said hollow stud serving to permit the introduction of cables into the box, a body of insulating material disposed within the casing, said body having a raised central portion, a set of metallic terminals mounted on one face of the body, an electric socket on said raised central portion and a cap holding the elements in assembled relation.

7. A combined outlet box and connecting device comprising a casing having formed integrally therewith a plurality of hollow studs

serving to permit the introduction of cables into the box, a body of insulating material disposed within the casing, a set of metallic terminals mounted on said body at opposite ends thereof, a metallic socket having an interiorly threaded longitudinal passage, said socket being disposed on said insulating body, a raised central portion on said insulating body fitting into said passage and a cap for holding said elements in assembled relation.

8. A combined outlet box and connecting device comprising a casing having a plurality of hollow studs formed integrally therewith and disposed on the bottom thereof and reaching to a height substantially below the top of the casing, a body of insulating material disposed on the bottom of said casing and having a surface on the level of the upper ends of said studs, a metallic socket resting on said body of insulating material and having an interiorly threaded longitudinal passage, said body of insulating material having a raised central portion fitting into said passage and a cap for holding the elements in assembled relation.

9. A combined junction and outlet box comprising a casing having a plurality of openings to admit the lead-in wires and the

take-off wires, a body of insulating material disposed within said casing, a set of distributing plates mounted on said body, a plurality of binding posts mounted on each of said plates for connection with the said wires, a socket mounted on said body, said socket comprising a metallic block electrically connected to one of said terminals and a cover for holding said parts in assembled relation.

10. An electric supporting and connecting device comprising a casing, having a plurality of inlets adapted to receive armored cables, an insulating body disposed in said casing, a pair of terminal plates mounted on said body, a plurality of binding posts on each of said terminal plates, said binding posts being adapted to connect said cables to said terminal plates, a socket electrically connected to said terminal plates, said socket comprising a metallic block adapted to electrically connect a fixture and to support the weight of said fixture, a cover for said casing and means for holding said elements in assembled relation.

In testimony whereof I have hereunto affixed my signature.

SAMUEL JACOB AARON.
